(57) **CLAIM**

We claim the ornamental design for the control panel, as shown.

DESCRIPTION

FIG. 1 is a first perspective view of the control panel, the handle being tilted upward from the base;

FIG. 2 is a second perspective view, showing the control panel and handle rotated relative to FIG. 1 and the handle tilted downward from the base;

FIG. 3 is a front elevation view of the control panel with the handle in a vertical upright position relative to the base;

FIG. 4 is a rear elevation view thereof;

FIG. 5 is a left side elevation view thereof;

FIG. 6 is a right side elevation view thereof; and,

FIG. 7 is a plan view thereof.

1 Claim, 7 Drawing Sheets(56)
